HEAT-INSULATED FLOOR

Carl Georg Munters, Stocksund, Sweden

Application January 5, 1943, Serial No. 471,344
In Sweden September 8, 1941

4 Claims. (CL. 94—3)

This invention relates to heat-insulated floors, particularly for cold-storage rooms. More particularly the invention relates to floors comprising a layer of heat-insulating material placed on a substructure and a layer of concrete lying on top of the first-mentioned layer, said concrete layer being carried by supports extending from the substructure through the insulating layer. The invention has for its main objects to provide a floor of this type which is inexpensive with respect to the erection cost and which possesses great strength and a good insulating capacity.

Further objects and advantages of the invention will be apparent from the following description considered in connection with the accompanying drawing which forms a part of this specification, and of which:

Fig. 1 shows a plan view of a portion of a floor in accordance with the invention, the concrete layer being partly broken away.

Fig. 2 shows a section on the line II—II of Fig. 1.

In the drawing, 10 designates the substructure of a floor, which may be made from concrete, for example, said substructure having insulation boards or units 12 of the multilayer type provided thereon. Narrow ribs 14 extending along the floor are set on edge between the insulation board 12, said ribs bearing with the lower portion thereof on the substructure 10 while projecting with their upper portion for a distance above the boards. The ribs 14, which may consist of a material such as Eternite, carry steel reinforcing rods 16 or the like which are preferably placed crosswise over the surface of the floor, as will be seen from the drawing. A layer 18 of concrete of a suitable thickness is cast on the insulation units 12, the reinforcing rods 16 being thus embedded in their entirety within the concrete so as to reinforce the latter in the usual way. Inasmuch as the ribs 14 extend above the insulation boards 12, the upper ends thereof are also cast into the concrete. The ribs are thus locked in position, so as to permit of being made very thin relatively to the height thereof. During the erection of the floor, that is to say, during the casting of the concrete layer 18, and before the latter has set, the insulation boards serve as supports for the thin ribs 14. The erection is thus very simple, since it is only necessary to place a rim between two insulation boards and to push the latter into contact with the rib.

The insulation boards preferably consist of

alternate corrugated and plane sheets of paper, which are joined to each other by means of waterglass or the like, and which are impregnated with bituminous products. Insulation boards of this type have been found to withstand the weight of the concrete layer 18 during pouring and prior to the setting of the latter, without any compression of the boards taking place, which compression would reduce the insulating capacity of the boards. The insulation boards are placed with the corrugations of the sheets extending substantially parallel to the ribs 14. By this arrangement there will be formed open passages along the surface of the floor, which may be connected into a circulation system comprising the floor and wall insulation of the cold-storage room as well as the room itself as shown in the copending application 449,240 of C. G. Munters and D. E. Ahlqvist.

20 Two insulation boards 12 lying adjacent one another between two ribs 14 may be spaced a small distance from one another, so that an open circulation path for the air will be obtained with certainty even at the transition between the boards.

While a more or less specific embodiment of the invention has been shown, it is to be understood that this is for purpose of illustration only, and that the invention is not to be limited thereby, but its scope is to be determined by the appended claims viewed in the light of the prior art.

What I claim is:

1. A heat insulated floor comprising a substructure, a plurality of spaced relatively thin rib members set on edge on said substructure, heat insulating material supported on said substructure between said rib members, reinforcing rods supported by said rib members, and a layer of concrete on said insulating material and surrounding said reinforcing rods.

2. A heat insulated floor comprising a substructure, a plurality of spaced relatively thin rib members set on edge on said substructure, heat insulating material supported on said substructure between said rib members, the upper edges of said rib members extending above said insulating material, reinforcing rods bearing directly on said upper edges, and a layer of concrete on said insulating material and surrounding said reinforcing rods and the portions of said rib members which extend above said insulating material.

3. A heat insulated floor comprising a substructure, a plurality of spaced relatively thin

rib members set on edge on said substructure, multilayer heat insulating material having air spaces between the layers, said material being supported on said substructure between said rib members, reinforcing rods supported by said rib members, and a layer of concrete on said insulating material and surrounding said reinforcing rods, the layer of said insulating material having sufficient strength to support said concrete during the pouring and setting thereof without substantial reduction in the volume of said air spaces.

4. A heat insulated floor comprising a substructure, a plurality of spaced relatively thin rib members set on edge on said substructure and multilayer corrugated heat insulating material supported on said substructure between said rib member, the corrugation of said material extending substantially parallel to said rib members, reinforcing rods supported by said rib member, and a layer of concrete on said insulating material and surrounding said reinforcing rods.

CARL GEORG MUNTERS.
